DOOR CONTROLLING DEVICE

George C. Christy, Chicago, Ill.

Application February 28, 1935, Serial No. 8,627

2 Claims. (Cl. 292—53)

This invention relates to door controlling devices and has for its object to provide a new and improved device of this description.

The invention has as a further object to provide a door controlling device which automatically stops and holds the door in any desired position.

The invention has as a further object to provide a door controlling device wherein the movement of the handle for moving the door renders inoperative the holding device that holds the door in any given position.

The invention has as a further object to provide a door controlling device for controlling laterally movable doors.

The invention has as a further object to provide a door controlling device which is mounted on the door and forms a part thereof.

The invention has as a further object to provide a door controlling device particularly adapted for the sliding doors of cars.

The invention has as a further object to provide a door controlling device for a laterally movable door of a car which automatically prevents the lateral movement of the door in either direction due to movement or stopping of the car.

The invention has other objects which are more particularly pointed out in the accompanying description.

Referring now to the drawings, Fig. 1 is a view of one form of door controlling device embodying the invention;

Fig. 2 is an enlarged view of the bottom part of the door showing the position of the parts when the handle is moved in the direction of the arrow to move the door;

Fig. 3 is a view similar to Fig. 2 showing the handle in the central position and the door locked against movement;

Fig. 4 is a sectional view taken on line 4—4 of Fig. 3;

Fig. 5 is a sectional view taken on line 5—5 of Fig. 3 with the upper part of the door in section added thereto;

Fig. 6 is a view similar to Fig. 2 showing a modified construction of door controlling device;

Fig. 7 is a sectional view taken on line 7—7 of Fig. 6.

Like numerals refer to like parts throughout the several figures.

Referring now to the drawings wherein for purposes of illustration I have shown the door controlling device in connection with a laterally movable car door, it is of course evident that it

may be used with other kinds of doors and other differently constructed doors.

In Figure 1 the car door 1 is shown as a laterally movable car door. At the bottom of the door are rollers 2 and 3 which engage a track 4, the door rolling along this track. One of the difficulties of such a door is that when the car gives a sudden move, the door will move, and also when the car is suddenly stopped. This often causes the door, if it should be unlocked, to move back and forth and be battered at the ends of its travel and injured by such battering. This movement is something that it is exceedingly desirable to prevent.

In the construction shown in Figs. 1, 2, 3, 4, 15 and 5 the controlling device is attached to the door and forms a part thereof. In its simple form the device consists of a plate 5 which is attached to the door in any desired manner, as by the fastening devices 6. Mounted in proximity to this plate and preferably mounted thereon are the control members 7 and 8, preferably pivotally connected in position. In Figures 1 to 5 I have shown two separate controlling members 7 and 8 pivoted at 9 and 10 to a suitable fixed part 20 on the door, which may be the plate 5. These controlling members are provided with engaging ends 11 and 12 which engage a fixed part 4 associated with the device with which the door is used. A handle 14 is suitably located to be 25 grasped by anyone on the ground, and this handle is arranged so that when pressure is applied to it to move the door, it will release the controlling device which holds the door against this movement.

Any suitable connection between the handle and the controlling members may be utilized. In the particular construction shown, the plate 5 is provided with a slot 15 through which the handle 14 projects. Connected with this handle 30 on the inside of the plate is a piece 16 which covers the slot when the handle is in any of its various positions. There is also connected with the handle 14 an actuating part 17 which moves one of the control members to its inoperative position 35 when the handle is moved in one direction, and which moves the other controlling member to an inoperative position when the handle is moved in the opposite direction. In the construction shown this is accomplished by the actuating part 40 17 being located between the control members, as clearly shown in Fig. 4. The control members are enclosed between the plate 5 and the part 18, which may be the door itself or some part associated therewith so that the control mechanism 45 50 55

is inaccessible and hidden from view. At the top of the door there are usually provided guides **1a** which engage stationary parts **1b** on the car, a portion of the guides **1a** projecting under the part **1b**.

In Figs. 6 and 7 I have shown a modified construction wherein the two control members **7a** and **8a** are mounted upon the same pivot **8b**. The other parts are similar to the construction shown in Figs. 1 to 5 inclusive.

While in Figures 1 to 5 inclusive I have shown the device applied to a metal door, I have in Figures 6 and 7 shown the device applied to a wood door. In this construction there is an opening 15 cut in the bottom of the door and the plate **19** to which the control members are connected by the pivot **8b**, is fastened to the outside of the door by the fastening devices **20**. There is a rear plate **21** and the control members **7a** and **8a** are 20 between the plates **19** and **21**. The pivot **8b** preferably passes through both of the plates. The control members are preferably cut away at their upper ends so as to overlap, as clearly shown in Fig. 7. The engaging ends **22** and **23** engage the part **24** of the device with which the door is used. The handle **25** passes through the slot **26** in the plate **19** and has an engaging part **27** which projects between the control members **7a** and **8a**. There is a closure **28** for the slot **26**.

I have described in detail certain particular constructions embodying the invention, but it is of course evident that the parts may be changed in form, construction and arrangement, and some of the parts omitted and others used which are not herein shown, without departing from the spirit of the invention as embodied in the claims hereto appended, and I therefore do not limit myself to the particular construction shown.

The use and operation of my invention are as follows:

The door **1** in Fig. 1 is shown down on the rollers 2. When the handle of the car is free, that is, is released, it stands intermediate the control members, and these control members are in the 45 position shown in Fig. 3, wherein the engaging ends **11** and **12** engage the part **4** and the door is lifted off of the rollers so that it cannot be accidentally moved in either direction. I prefer to have the parts **1a** and **1b** so related so that when 50 the door is thus lifted off the rollers, the part of the guide **1a** under the part **1b** engages said part **1b**, or the top edges of the door may engage a fixed opposed part, so as to assist in holding the door against movement.

When it is desired to move the door, the handle **14** is grasped. If the handle is moved in the direction of the arrow, that is to the right in Fig. 2, the actuating part **17** engages the control member **7** and moves its lower end **11** outwardly and upwardly so as to release it from engagement with the part **4**. The door can now be moved to the right, as this movement causes the lower end 60 of the control member **12** to move outwardly and upwardly so as to release the door, the door then

coming down upon its rollers and being easily moved to any desired position. If the door is to be moved in the opposite direction, the handle **14** is moved in the opposite direction, moving the end **12** of the member **8** outwardly and upwardly, 5 freeing the door so that it may be easily moved. When the handle is released, the lower ends of the control members are in engagement with the opposed part **4**. Under these conditions a slight movement of the door in either direction causes 10 the lower end of one of the control members, depending upon which way the door is moved, to be moved inwardly to securely engage the part **4** and lift the door from the rollers and hold it against any accidental movement. When the handle **14** is grasped and moved in either direction, 15 it releases the control member to which it applies pressure and permits the door to be moved so as to release the other control member and the door rests on the rollers and can be moved 20 to the point desired.

The operation of the device in Figures 6 and 7 is similar in every respect to that above set out.

It will therefore be seen that I have here a simple, inexpensive control device which prevents accidental movement of the door in either direction, but which permits its easy movement in either direction when the handle is grasped.

It will further be noted that the same handle which is used to move the door, also acts to release the control members. This device, therefore, does not require the operator to do anything different from what he does with the ordinary door, for he grasps the handle just like he grasps the handle of the ordinary door and applies pressure to it, and this releases the control members and causes the door to move to the desired position. When he releases the handle, the control members act to raise the door and prevent accidental movement in either direction.

I claim:

1. A door controlling device comprising a movable handle for moving the door to open and close it, a lifting mechanism with which said handle is associated connected with said door for lifting and supporting the door when pressure is applied to the door at a point separate from the handle when the handle is released, said handle having a controlling engagement with said lifting device, the movement of the handle, for the purpose of opening or closing the door, rendering said lifting mechanism inoperative, said handle being separate from said lifting mechanism.

2. A door controlling device comprising a door lifting mechanism connected with the door for lifting and supporting the door when pressure is applied to the door at a point separate from the handle, a handle for moving the door to open and close it, and an operative connection between said handle and the door lifting mechanism for rendering said lifting mechanism inoperative when pressure is applied to the handle to move the door.

GEORGE C. CHRISTY.
